CLAIM

The ornamental design for a towel hanger, as shown and described.

DESCRIPTION

FIG. 1 is a front perspective view of the towel hanger showing my new design in one of many possible arrangements of its sliding elements;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a front perspective view of the towel hanger in a second of many possible arrangements of its sliding elements; and,

FIG. 9 is a front perspective view of the towel hanger in a third of many possible arrangements of its sliding elements. The invention is a device for hanging towels.
